UNITED STATES PATENT OFFICE.

ANDREW M. CLOUGH, OF BATAVIA, NEW YORK.

TIMBER-HOOK.

1,306,802.

Specification of Letters Patent. Patented June 17, 1919.

Application filed January 4, 1919. Serial No. 269,689.

To all whom it may concern:

Be it known that I, ANDREW M. CLOUGH, a citizen of the United States, residing at Batavia, in the county of Genesee and State 5 of New York, have invented certain new and useful Improvements in Timber-Hooks, of which the following is a specification.

This invention relates to unloading apparatus and more particularly to a novel form 10 of hook or grapple especially designed for unloading cross-ties, rail girders, beams and the like from gondola cars.

The object of the invention is to provide a timber hook of simple and durable construction by means of which cross-ties may be conveniently elevated from a car and the gripping jaws of the hook instantly released to drop the load at any desired point in the travel thereof.

20 The invention further aims to provide a timber hook including coacting gripping jaws and an intermediate stem upon which is slidably mounted a combined holding and releasing member, the latter being attached 25 to a draft line and so arranged that a longitudinal pull on the draft line will actuate said member to open the jaws and release the load, and when the line is slack said member will drop by gravity to locking position.

30 The invention further contemplates a timber hook the gripping jaws of which are provided with terminal handles so as to permit said jaws to be manually moved to open position to grip a cross-tie independently of the combined releasing and locking device.

A still further object of the invention is generally to improve this class of devices so 40 as to increase their utility, durability and efficiency.

In the accompanying drawings:

Figure 1 is a front elevation of a timber hook embodying the present invention showing in full lines the combined locking and releasing member in lowered position and in 45 dotted lines the position assumed by the gripping jaws when said member is in elevated position;

50 Fig. 2 is a side elevation;

Fig. 3 is a transverse sectional view taken on the line 3-3 of Fig. 1 and looking in the direction of the arrows.

The improved timber hook forming the

subject-matter of the present invention 55 comprises a cross-head preferably formed of spaced relatively flat bars 5 between which is interposed and rigidly secured the enlarged head 6 of a vertically disposed stem 7. The upper end of the stem 7 is 60 bifurcated at 8 for the reception of a clevis 9, the latter being retained in position on the stem by means of a pin 10 and having its upper end attached to an elevating cable 11 leading to a crane of any suitable construction and indicated conventionally at 12. Arranged on opposite sides of the head 6 and pivotally mounted at 13 between the plates comprising the cross-head are gripping members or hooks 14 having terminal 70 inwardly extending bills or spurs adapted to bite into the cross-tie and prevent accidental displacement thereof during the unloading operation. The hooks 14 are provided with diverging extensions 15 to the 75 upper ends of which are secured suitable loops or handles 16 for the purpose of manually opening the jaws to grip a cross-tie prior to unloading said tie from the car. The plates 5 comprising the cross-head are 80 preferably formed with a plurality of transverse openings 17 so that by changing the position of the pivot pins or bolts 13 the jaws 14 may be spaced at any desired distance 85 apart so as to grip cross-ties and other objects of different sizes.

Slidably mounted on the stem 7 is a combined gripping and locking member 18, the latter being preferably substantially spherical in shape and having a longitudinal 90 opening extending through the center thereof to permit the passage of the stem 7. Encircling the extensions 15 of the gripping jaws are guiding loops or keepers 20 each provided with a threaded shank 21 95 which engages a correspondingly threaded opening formed in the member 18, said guiding loops or keepers being loosely mounted on the extensions 15 so as to prevent binding or wedging action between the 100 parts when the member 18 is moved to elevated or lowered positions. Threaded in the upper surface of the combined releasing and locking member 18 and preferably offset with respect to the stem 7 is an attaching eye 22 to which is secured one end of a draft cable 23, the other end of said draft cable being extended over a sheave or 105

pulley 24 on the crane 12 with its terminal disposed within convenient reach of the operator of the crane. The upper surface of the head 6 is preferably curved or 5 rounded and projects slightly above the upper longitudinal edges of the plates 5 constituting the cross-head so as to form in effect a bumper and receive the impact of the member 18 under certain conditions.

- 10 It will here be noted that the inclination of the inner longitudinal edges of the extensions 15 corresponds to the inclination of the side walls of the member 18 so that when the handles 16 are manually forced together 15 the member 18 will ride upwardly on the stem 7 to the dotted line position shown in Fig. 1 of the drawings. When the handles 16 are released the member 18 will drop by gravity to lowered position between the inner longitudinal edges of the jaw extensions and thus lock the gripping ends of 20 said jaws in engagement with the cross tie or other object to be elevated. It will, of course, be understood that the extent of 25 downward movement of the member 18 is controlled by the spread of the active ends of the gripping jaws and that when gripping relatively narrow objects the head 6 will form a buffer and receive the impact of 30 the member 18.

In unloading cross-ties and the like from gondola cars the workman on the car moves the jaws to open position by pressing inwardly on the handles 16 and then positions the jaws over one of the cross-ties to be elevated. As soon as the handles are released the downward movement of the member 18 will force the jaws to closed position and hold them securely in engagement 35 with the tie. The workman or attendant on the crane then operates the latter to elevate the cross-tie and when said cross-tie has reached the desired height and has been 40 swung laterally to one side of the car, the load man be released by merely exerting a 45 longitudinal pull on the draft cable 23 which moves the member 18 to elevated position thereby opening the jaws and permitting the cross-tie to drop at the side of 50 the car, or at any other convenient place where it is desired to deposit the ties.

While the hook or grapple is particularly designed for loading and unloading railway cross-ties it will, of course, be understood 55 that the device may be used with equally good results for handling rail girders, metallic beams and the like without departing from the spirit of the invention.

Having thus described the invention, what 60 is claimed as new is:

1. An unloading device including pivotally united jaws having extensions, a stem interposed between the jaws, an elevating device connected with the stem, a combined 65 releasing and locking member slidably

mounted on the stem, a connection between the jaw extensions and said member, the member being movable downwardly to locking position between the extensions of the jaws, and means for elevating said member 70 to release the jaws and permit discharge of the load while the latter is in suspension.

2. An unloading device including a cross-head, a stem secured to the cross-head, an elevating device connected with the stem, 75 coacting gripping jaws pivotally mounted on the cross-head and provided with diverging extensions, a combined releasing and locking member slidably mounted on the stem, a connection between said member and 80 the extensions of the jaws, said member when in lowered position serving to hold the jaws in engagement with the load, and means connected with said member for elevating the latter on the stem to move the 85 jaws to open position and release the load while the latter is in suspension.

3. An unloading device including a cross-head, a stem secured to the cross-head and provided with means for attachment to an 90 elevating cable, jaws pivotally mounted on the cross-head and provided with diverging extensions, a combined releasing and locking member slidably mounted on the stem, 95 guiding loops encircling the jaw extensions and secured to said member, and a draft cable operatively connected with said member for elevating the same on the stem to move the jaws to open position and release the load while the latter is suspended by the 100 elevating cable.

4. An unloading device including a cross-head, a stem secured to the cross-head, and provided with means for attachment to an elevating cable, gripping jaws pivotally 105 mounted on the cross-head and provided with diverging extensions terminating in handles, a combined releasing and locking member slidably mounted on the stem, guiding members engaging the extensions of the 110 gripping jaws and secured to said member, and a draft line connected with said member for actuating the same to release the jaws and permit discharge of the load while the latter is suspended by the 115 elevating cable.

5. An unloading device including a cross-head formed of spaced plates, a stem interposed between said plates and provided with means for attachment to an elevating cable, 120 gripping jaws pivotally mounted between the plates of the cross-head and provided with diverging extensions terminating in handles, a combined releasing and locking member slidably mounted on the stem, loops 125 encircling the extensions of the jaws and engaging said member, and an eye secured to the upper end of the said member and offset with respect to the stem for attachment to a draft line, said member being operable to 130

release the jaws and permit discharge of the load while the latter is suspended by the elevating cable.

6. An unloading device including a cross-head, a stem secured to the cross-head and provided with means for attachment to an elevating cable, gripping jaws pivotally mounted on the cross-head on opposite sides of the stem and provided with diverging extensions, a substantially spherical combined releasing and locking member slidably mounted on the stem, guiding members carried by said member and engaging the extensions of the gripping jaws, and means attached to said member for elevating the same to move the jaws to open position and release the load while the latter is suspended by the elevating cable, said member being

movable by gravity to lowered position between the extensions of the jaws and serving 20 to hold said jaws closed.

7. An unloading device including pivotally united jaws, a stem arranged between said jaws, an elevating device connected with the stem, a combined releasing and locking member slidably mounted on the stem and coöperating with the jaws for holding the jaws in engagement with the load, and means connected with said member for elevating the same thereby to release the 30 jaws and permit discharge of the load while the latter is suspended by the elevating device.

In testimony whereof I affix my signature.

ANDREW M. CLOUGH. [L. S.]
